Patented Oct. 6, 1925.

UNITED STATES PATENT OFFICE.

MARY V. BRUNK, OF KANSAS CITY, KANSAS.

GARMENT FASTENER.

Application filed December 28, 1923. Serial No. 683,153.

To all whom it may concern:

Be it known that I, MARY V. BRUNK, a citizen of the United States, residing at Kansas City, in the county of Wyandotte 5 and State of Kansas, have invented certain new and useful Improvements in Garment Fasteners, of which the following is a specification.

My invention relates to a new article of manufacture and the method of forming the same, and one important feature resides in the provision of flexible buttons which may be laundered with the garments to which they are sewed, without danger of their being pulled off or broken, as often happens with buttons made of pearl, bone, or other hard material.

The present buttons may be made of the same goods as the garment, or of any other desired goods, and they are preferably sewed to a strip of fabric which in turn is sewed to the garment, and as they have no holes through which the needle must be directed as with hard buttons the operation of sewing them to said strip, or directly to the garment, may be speedily accomplished.

A further object of the invention is to provide a strip with button holes of peculiar form through which the flexible buttons 30 may be readily passed, and the margins of which can be sewed more rapidly than the margins of the usual form of button holes.

In order that the invention may be fully understood, reference will now be had to the accompanying drawing, in which:

Fig. 1 is a broken elevation of a garment provided with the buttons and button holes.

Fig. 2 is a broken sectional view showing one style of button hole.

Fig. 3 is a broken elevation of a strip of fabric provided with the flexible buttons.

Fig. 4 shows a strip of fabric with two of its margins sewed together to form a tube constituting the first step in one method of forming the flexible button.

Fig. 5 is a section showing the final step of forming a square button from the tube disclosed by Fig. 4.

Fig. 6 is a perspective view showing how 50 the square button disclosed by Fig. 5 may be formed into an eight-sided button, before the several folds are sewed together.

Fig. 7 is a detail of the completed eight-sided button.

Fig. 8 is a detail of a circular button.

Fig. 9 is a broken elevation of a garment provided with the circular buttons and peculiar shaped button holes through which said buttons may be passed.

Fig. 10 is a broken detail of a fabric strip 60 in which a portion of each button hole is formed.

Referring now more particularly to the form disclosed by Figs. 1 to 5, inclusive, 2 designates an undershirt formed of knitted goods reinforced at opposite sides of its opening 3 with strips of tape or other suitable fabric 4 and 6. The strip 6 has a similar strip 7 sewed thereto in such manner as to leave button holes 9 at suitable intervals. 70 The strip 4 is provided with a plurality of flexible buttons 8 which may be made of one or more thicknesses of material to give them the necessary body or stiffness to prevent accidental withdrawal from the button holes. 75

One desirable method of forming each button 8 consists in taking a strip of fabric and sewing two of its margins together as indicated at 10, thereby forming a tube 12. The ends 14 are then turned within said tube 12, as shown by Fig. 5, and secured by stitching 16. If desired additional rows of stitching may be added as it lends to the stiffness of the button and overcomes accidental withdrawal from the button hole 9 through which the button is inserted by folding two of its opposite corners together. 85

After the buttons 8 have been formed as stated, they may be sewed directly to the garment or to a strip such as 4, either operation being quickly accomplished as the buttons have no holes requiring care and time in directing the needle through, as with the ordinary nonflexible buttons.

If it is desired to make an eight-sided 95 button instead of a square button, the latter, after being folded to the form disclosed by Fig. 5, and before being stitched, has its four corners folded inwardly as shown by Fig. 6, after which the different folds may 100 be held together by stitching 20 as shown by Fig. 7.

In strong goods not likely to unravel the reinforcing strips 4 and 6 can be dispensed with and a strip such as 6^a with V-shaped 105 openings 9^a may be sewed directly to one margin of the garment 2^a as shown by Fig. 9. The V-shaped openings 9^a are, preferably, used where round buttons 8^a are employed as the same when folded can be 110

passed through the V-shaped button holes more readily than through the narrow button holes 9. Any of the buttons above described reliably hold the garment closed by 5 overlapping the button holes, but can be easily unbuttoned by the wearer.

Garments such as underwear, aprons, dresses, etc., equipped with the flexible buttons above described can be run through 10 washing machines, wringers, mangles, etc., without danger of pulling off or mutilating said buttons, and as the buttons may be made from the same class of goods which compose the garments they present a neat 15 and attractive appearance.

While I have shown and described several

forms of buttons and button holes, I reserve the right to such other forms as properly fall within the spirit and scope of the invention as claimed.

20

Having thus described my invention, what I claim and desire to secure by Letters Patent, is:

The method of manufacturing a button consisting of forming a strip of fabric into 25 a tube, folding the ends of said tube within itself, folding the corners of said tube inwardly, and stitching the folded portions to hold them in place.

In testimony whereof I affix my signature.

MARY V. BRUNK.
